UNITED STATES PATENT OFFICE.

FREDERICK A. STERN, OF NEW YORK, N. Y.

DESIGN FOR A DRINKING CUP.

Application filed July 3, 1928. Serial No. 27,370. Term of patent 14 years.

To all whom it may concern:

Be it known that I, FREDERICK A. STERN, a citizen of the United States and a resident of New York, in the county and State of New York, have invented a new, original, and ornamental Design for Drinking Cup, of which the following is a specification, reference being had to accompanying drawing, forming a part thereof in which—

Fig. 2 is a perspective view looking down from the top of a drinking cup showing my new design.

I claim:

The ornamental design for a drinking cup, as shown.

Signed at New York, in the county and State of New York, this 2nd day of July, 1928.

FREDERICK A. STERN.
